UNITED STATES PATENT OFFICE

JOHN H. DOMKEE, OF WEST HAVEN, CONNECTICUT, ASSIGNOR TO THE WIRE NOVELTY MANUFACTURING COMPANY, OF WEST HAVEN, CONNECTICUT, A CORPORATION OF CONNECTICUT

BUTTON LOOP

Application filed March 7, 1930. Serial No. 434,109.

This invention relates to improvement in button loops adapted for use on garment straps for suspension at the end of a strap in readiness to be clipped over a button the shank of which may be urged therefrom into a smaller retaining loop from which it cannot be unintentionally withdrawn, and the objects of the invention are to provide a button loop of resilient wire of which portions cooperate to form an expandible button-retaining loop, and to provide for such a button-retaining loop a novel means for mounting a clip coupling thereon. With these and other objects in view as may become apparent from the within disclosures, the invention consists not only of the particular form herein pointed out and illustrated in the drawing but readily admits of certain modifications within the scope of what hereinafter may be claimed.

The following is the description of an embodiment of the invention the character of which may be best understood by reference to one illustrative device as illustrated by the accompanying drawing in which the Fig. 1 is a front elevation of the device in normal condition; the Fig. 1a is a side elevation of the same; the Fig. 2 is an upright front view of the wire portion of the device; the Fig. 3 is a sheet metal stamping of one form of clip coupling; the Fig. 3a is a side elevation of the completed coupling; the Fig. 4 is a front view of the clip in expanded condition; the Fig. 5 is a sheet metal stamping of another form of clip coupling; the Fig. 5a is a side elevation of the completed coupling; the Fig. 6 is a fragmentary front elevation of the wire loop with the modified coupling applied thereto; and the Fig. 6a is a side elevation thereof.

Referring more particularly to the drawing in which similar numbers refer to similar parts, the device comprises a piece of resilient wire of which a middle portion is bent to form the suspension loop 1, the other wire portions depending therefrom and providing the spring arms 2 and 3 cooperating to form the axially associated button-receiving and button-retaining loops 4 and 5, respectively, having the intermediate normal-

ly contracted throat portion 6. The wire end portions are bent away from the loops in an axial direction and then immediately bent at right angles and in opposite directions to provide the normally abutting elbows 7 and 8 and the laterally outwardly aligned bars 9 and 10, as best illustrated by the Figure 2. Any clip coupling mountable upon the extremities of the aligned bars 9 and 10 so as to permit a limited freedom of sliding movement of the bars relative thereto may be provided, but the preferred form of clip coupling illustrated by the Figs. 3 and 3a is a sheet metal stamped form having the body portion 12 with the central perforation 13 and the arms 11 each of which is adapted to be rolled, as illustrated by the Figure 3a, for a sliding mounting upon an aligned bar 9 or 10, the body portion being folded upon the dotted line 14, within the button-retaining loop 5, and enclosing the elbows 7 and 8 and adjacent wire portions, the perforation 13 after folding the body portion 12 providing a seat for the shank S of a button, as illustrated by the Figure 1, the shank-seat intercepting the button strain and thus preventing the accidental release of the shank between the elbows 7 and 8, the button strain upon the shank-seat being supported by the arms 11 mounted upon the aligned bars 9 and 10. As the shank S passes through the throat portion 6 the button loop expands as illustrated by the Figure 4, the normally abutting elbows 7 and 8 relatively parting and the aligned bars 9 and 10 each sliding within its respective rolled arm 11 and slightly projecting beyond the clip coupling. The resiliency of the spring arms 2 and 3 is relied upon to return the throat portion 6 to its normally contracted condition and hence the elbows 7 and 8 to their normally abutting relation.

The Figure 5 illustrates a modified form of a clip coupling stamping having a body portion folded upon the dotted line 14A to form the completed coupling shown in Fig. 5a and enclosing the aligned bars 9 and 10, the indentations 11A securing the clip upon the bar extremities, and the relatively spaced arcuate

portions 13A cooperating to provide the seat for the button-shank S.

The button loop in either preferred or modified form is reversible and therefore is adapted to be mounted upon a strap to prominently display the front elevation thereof as illustrated or an opposite elevation not illustrated by reason of the fact that both elevations are substantially similar.

10 I claim:—

1. A button loop comprising spring arms cooperating to form axially associated loops having an intermediate normally contracted throat portion, the end portions of the arms being bent laterally outwardly in alignment, one with the other; and a clip coupling suspended from within one of the loops and having sleeves encompassing the aligned portions of the arms, the aligned portions being movable within said sleeves upon the expansion of the throat portion.

2. A reversible button loop comprising spring arms cooperating to form a button-receiving loop, a button-retaining loop axially associated with the receiving loop and being of circular formation, and an intermediate normally contracted throat portion, the end portions of the arms being bent laterally outwardly in alignment, one with the other; and a clip coupling suspended from within one of the loops and having sleeves encompassing the aligned portions of the arms, the aligned portions being movable within said sleeves upon the expansion of the throat portion.

3. A reversible button loop comprising spring arms cooperating to form a button-receiving loop, a button retaining loop axially associated with the receiving loop, and an intermediate normally contracted throat portion, the end portions of the arms being bent laterally outwardly in alignment, one with the other; and a clip coupling having sleeves mounted upon the aligned portions of the arms, the aligned portions being relatively movable within the sleeves upon the expansion of the throat portion, the clip having a part extending through and foldingly enclosing a portion of the retaining loop to provide within the loop a seat for the shank of a button.

4. A reversible button loop comprising a piece of resilient wire of which a middle portion is bent to form a suspension loop, the other wire portions providing spring arms cooperating to form axially associated loops having an intermediate normally contracted throat portion, the wire end portions being bent laterally outwardly in alignment, one with the other; and a clip coupling having sleeves mounted upon the aligned portions of the arms, the aligned portions being movable within the sleeves upon the expansion of the throat portion, the clip having a part extending through and foldingly enclosing a portion

of the adjacent loop to provide within the loop a seat for the shank of a button.

5. A reversible button loop comprising a piece of resilient wire of which a middle portion is bent to form a suspension loop, the other wire portions providing spring arms cooperating to form a button-receiving loop, a button-retaining loop axially associated with the receiving loop, the retaining loop being of circular formation, and an intermediate normally contracted throat portion, the wire end portions being bent laterally outwardly in alignment, one with the other; and a clip coupling having sleeves mounted upon the aligned portions of the arms, the aligned portions being relatively movable within the sleeves upon the expansion of the throat portion, the clip having a part extending through and foldingly enclosing a portion of the circular loop to provide within the loop a seat for the shank of a button.
